UNITED STATES PATENT OFFICE.

HENRY JOHNSON, OF NEW YORK, N. Y., ASSIGNOR TO M. NICHOLS JOHNSON,
OF SAME PLACE.

PAPER-CUTTER.

SPECIFICATION forming part of Letters Patent No. 257,949, dated May 16, 1882.

Application filed October 27, 1880. (No model.)

To all whom it may concern:

Be it known that I, HENRY JOHNSON, of the city of New York, in the county and State of New York, have invented certain Improvements in 5 Paper-Cutting Machines, of which the following is a specification, reference being had to the annexed drawings, in which—

Figure 1 is a partial front elevation of a paper-cutting machine, showing my improved 10 mode of operating the cutting-knife. Fig. 2 is an end view of the knife-bar and hand-lever.

My invention relates to an improvement in hand-lever paper-cutters; and it consists in providing the outer end of the knife-bar with 15 an inclined slot, in which a pin on the bent hand-lever reciprocates for the purpose of giving the knife the requisite cutting motion.

My improved paper-cutting machine is represented in the accompanying drawings, in 20 which K is the knife-bar; l, one of its supporting-links; T, the table; S, one of the standards; C, the cross-head, and L the hand-lever.

The table, standards, and cross-head are constructed in the usual manner, and the machine is provided with a paper-clamp, arranged 25 to be operated up and down in grooves in the standards by a screw and hand-wheel.

The knife-bar K reciprocates in slots in the standards, and receives the well-known draw- 30 ing-cut motion from the supporting-links. The knife n is attached to the lower edge of the knife-bar, and the machine is provided with a sliding paper-gage on the table T, as usual.

The hand-lever L, by which the knife-bar 35 and knife are operated, is provided with a bent arm or offset, which projects inward, and is pivoted at a to lugs e on the standard S. In operating the knife-bar the lever L swings about the pivotal point a as a fulcrum, the po- 40 sition of the lever and the knife-bar, when the latter has completed its downward stroke, be-

ing shown in dotted lines L' K', Fig. 1. The lever is attached to the knife-bar by means of a pin, d, passing through an inclined slot, c, in the outer end of the knife-bar. The supporting-link l passes through a recess cored for it in the knife-bar, and is attached to a pin, which, for convenience of removal, is provided with a thread and nut at one end.

The lever L may be constructed with the 50 bent portion on one side only of the knife-bar; but I prefer, for the purpose of securing greater strength and durability, especially on machines of large size, to use a bifurcated lever, the inner ends of the bent arms thereof being pivoted to the lugs e on the standard S on each side of the knife-bar. The pin d is preferably provided with a friction-roller, sliding within the slot c, as represented by the dotted circle in Fig. 1. As the lever swings outward and 55 downward about the pivotal point a the roller travels backward and forward in the slot c, imparting a diagonal cutting motion to the knife-bar and knife. The downward inclination of the slot c in the outer end of the knife-bar 60 enables me to obtain an increased amount of travel for the knife, and it also equalizes the 65 application of the power during the cutting stroke.

I claim—

In combination with the knife and knife-bar of a paper-cutter, having a diagonal cutting motion, the lever L, provided with a bent arm pivoted to the frame at its inner end, and connected to the knife-bar by a pin passing through 75 an inclined slot in the knife-bar, substantially as and for the purposes described.

HENRY JOHNSON.
